[57] CLAIM

The ornamental design for a control panel for a luggage lock, as shown and described.

DESCRIPTION

FIG. 1 is a side elevational view of a control panel for a luggage lock showing my new design, the side opposite being a mirror image;

FIG. 2 is an end elevational view thereof, the end opposite being a mirror image;

FIG. 3 is a top plan view thereof, the bottom being plain and unornamented; and

FIG. 4 is an enlarged perspective view thereof.
The broken-line showing is for illustrative purposes only, and forms no part of the claimed design.

FIG. 1.***FIG. 2.******FIG. 3.****FIG. 4*
